(57) **CLAIM**

The ornamental design for a pill crusher pouch, as shown and described.

DESCRIPTION

FIG. 1 is a perspective view of a pill crusher pouch in an open position showing our new design;

FIG. 2 is a perspective view of the pill crusher pouch in an closed position view thereof;

FIG. 3 is a front elevation view of the pill crusher pouch in the closed position;

FIG. 4 is a rear elevation view of the pill crusher pouch in the closed position;

FIG. 5 is a right elevation view of the pill crusher pouch in a partially open position;

FIG. 6 is a left elevation view of the pill crusher pouch in the partially open position;

FIG. 7 is a bottom plan view of the pill crusher pouch in the partially open position; and,

FIG. 8 is a top plan view of the pill crusher pouch in the partially open position.

The broken line showing of the seam of the pouch is included for the purpose of showing portions of the article and form no part of the claimed design.
